ATTORNEYS

into the counterbores 24 and over the cylindrical screw heads 26. The gaps 36 snugly receive radial lugs 38, preferably diametrically opposed to one another and slightly wider than the gaps 36 so as to force the arcuate lug ends 34 apart from one another, and thereby wedge the arcuate lugs 32 tightly into frictional engagement with the side walls of the counterbore 24.

FIGURE 6 shows the closure 10 of FIGURES 1 to 5 inclusive as applied to a slightly modified toilet seat hinge leaf, generally designated 40, having an approximately T-shaped laterally-extending arm 42 widened relatively to the bore boss 44 thereof so that its fastener holes 46 with their counterbores 48 are disposed in a line perpendicular to the axis of the arm 12.

In the installation of the cover 10 of the fastener-concealing hinge leaf construction 8 either upon the hinge leaf 12 of the hinge leaf 40, the latter are first secured by their respective screws 16 to the toilet seat lid 14 (or seat, as the case may be), after which the pairs 30 of lugs 32 are lined up with their respective counterbores 24 and pushed into the counterbores 24. As the plate portion 28 is pushed toward the hinge leaf arm 20 or 42 into engagement with the arm surface 21, the arcuate lugs 32 snap into position on opposite sides of the cylindrical head 26 of the cylinder head screws 16 while at the same time the adjacent ends 34 at the gaps 36 are wedged apart by the lugs 38.

The cover, generally designated 50, shown in FIGURE 7 is applied to a hinge leaf 52 having a bored boss 54 and attachment arm 56 preferably widened at its outer end as in FIGURE 6 and equipped with either one or a pair of fastener holes 58 counterbored as at 60 with inwardly-projecting diametral wedging lugs 61 to receive the heads 62 of cylinder head screws 64 similar to the screws 16 of FIGURE 2 and similarly securing the hinge leaf 52 to the toilet seat lid 66. The cover 50 is provided with a plate portion 68 having at one end a pair of arcuate lugs 70 similar to the pairs 30 of lugs 32 of FIGURE 4 and similarly fitting the counterbore 60 around the cylindrical head 62 of the screw or screws 64 and wedged apart by the wedging lugs 61. Remote from the lugs 70, the arm 68 is provided with an angle portion 72 hooked around a rabbet 74 in the hinge leaf arm 56 into engagement with the shoulder 76 thereof.

The cover 50 is installed in a manner similar to the closure 10 by snapping the opposed arcuate lugs 70 into the counterbore or counterbores 50 after first lining up the angle portion 72 with the shoulder 76, which thereby serves as a pilot.

The further modified cover, generally designated 80, shown in FIGURES 8 and 9 is applied to an angle hinge leaf 82 shown in perspective in FIGURE 8 and provided with a bored boss 84 with an attachment arm 86 having fastener holes 88 and counterbores 90 for the cylindrical heads 92 of cylinder head screws 94. The hinge leaf 82 intermediate the fastener holes 88 is provided with a pilot hole or recess 96 disposed with its axis parallel to the parallel axes of the fastener holes 88. The cover 80 has a plate portion 98 with arcuate lugs 100 fitting into the counterbores 90 around the screw heads 92 and an integral pilot pin 102 projects upward from the plate portion 98 snugly into the pilot hole 96.

The installation of the cover 80 is similar to that of the closure 10 of FIGURES 1 to 6 inclusive except that the pilot pin 106 is first inserted in the pilot hole 96 and the plate portion 98 rotated around the pin 102 as a pivot until the pairs of arcuate lugs 100 are aligned with their respective counterbores 90. The operator then pushes the cover 80 into position by pressure upon the plate portion 98, as by applying his thumb.

The individual covers 110 of FIGURE 10 are applied to hinge leaves 12 identical with the hinge leaves 12 of FIGURES 1 to 5 inclusive and having similar fastener holes 22, counterbores 24 and fasteners 16 with cylindrical heads 26. The individual covers 110, however, as

their names suggest, are single and unconnected in contrast to the double-lug covers 10 of FIGURES 1 to 5 inclusive. Each cover 110 may therefore be termed a cover button with a disc portion 112 from which spaced

5 paired oppositely-facing arcuate lugs project in a manner similar to the lugs 32 of the closure 10 of FIGURE 4. As before, the counterbores 24 are provided with inwardly-extending diametral lugs 38 which engage and urge the ends of the arcuate lugs 114 apart from one another into frictional engagement with the side walls of the counterbores 24, in a manner similar to that shown in FIGURES 1 to 5 inclusive.

The additionally modified cover, generally designated 120, shown in FIGURES 11 to 13 inclusive is applied to 15 an angled hinge leaf 122 having the bored boss 124 and projecting arm 126. The latter, however, is provided on its opposite sides with grooves 128 which receive approximately L-shaped arms 130 projecting parallel to one another from the opposite edges 132 of the plate portion 134. The plate portion 134 fits into a correspondingly spaced recess 136 in the hinge leaf arm 126.

The installation of the cover 120 of FIGURES 11 to 13 inclusive is made after the hinge leaf 122 has been secured to the toilet seat or lid by fastening screws 138.

25 To do this, the operator brings the arms 130 into line with the side grooves 128 which serve as pilot grooves, after which he snaps the cover 120 into place by thumb pressure upon the plate portion 134 so that it fits snugly into the recess 136.

30 The cover, generally designated 140, shown in FIGURE 14 is applied to a hinge leaf 12 similar to that shown in FIGURES 1 to 5 inclusive and hence designated with corresponding reference numerals. The fastener screws 142 have half round heads 144 which, when installed, lie 35 within the counterbores 24. The heads 144 are covered by the filling material 140 of putty-like consistency when applied, such as a powdered synthetic plastic containing a hardening substance and which soon solidifies. This material is forced into the counterbore 24 by means of a 40 putty knife or other suitable tool and faced off with the adjacent surface 21 of the hinge leaf 12.

The finally modified cover, generally designated 150, shown in FIGURE 15 is of channel cross-section adapted to slide over a hinge leaf 152 having a bored head 154 (only part of which is shown) and attachment arm 156 with opposite sides 158 and undercut rabbets or grooves 160 forming shoulders 162 along the sides 158 remote from the surface 164 of the attachment arm 156. Counterbored screw holes 166 receive fasteners, such as round-headed screws 168, by which the hinge leaf 152 is attached to the toilet lid or seat (not shown).

The cover 150 roughly resembles the toe-box of a conventional shoe in that it has a top wall 170 from which side walls 172 extend approximately at right angles with 55 their edges 174 terminating in inwardly-projecting flanges 176. The top wall 170 and side walls 172 are interconnected by a forward or front wall 178.

Before installing the closure 150 of FIGURE 15, the hinge leaf 152 is secured to the toilet seat or lid (not shown) by the screws 168 in a manner similar to that shown in FIGURE 2. The operator then places the entrance 180 of the pocket 182 within the cover 150 adjacent the free end 184 of the hinge leaf arm 156 with the flanges 176 aligned with the rabbets 160 beneath the 65 shoulders 162. The operator then applies pressure to the end wall 178 to push the cover 150 onto the hinge leaf arm 156 while the flanges 176 slide along and engage the rabbets 160.

What I claim is:

70 1. A fastener-concealing hinge leaf construction comprising a hinge leaf having a fastener hole therethrough and a counterbore connected to said fastener hole, a fastener having a shank extending through said hole and an enlarged head seated in said counterbore,

a fastener cover engaging said hinge leaf and extending over said counterbore in concealing relationship therewith,
and means for securing said fastener cover to said hinge leaf,
said securing means comprising a projecting device on said cover extending into said counterbore in gripping engagement with the side wall thereof,
said projecting device including a pair of arcuate projections spaced apart from one another with a gap between adjacent ends thereof,
said hinge leaf having a lug projecting into said counterbore into the gap between said arcuate projections. 15

2. A fastener-concealing hinge leaf construction, according to claim 1, wherein said lug is slightly wider than said gap and thereby enters into wedging engagement with said projection ends. 20

3. A fastener-concealing hinge leaf construction comprising
a hinge leaf having a fastener hole therethrough and a counterbore connected to said fastener hole,
a fastener having a shank extending through said hole and an enlarged head seated in said counterbore,
a fastener cover engaging said hinge leaf and extending over said counterbore in concealing relationship therewith,
and means for securing said fastener cover to said hinge leaf,
said securing means comprising a projecting device on said cover extending into said counterbore in gripping engagement with the side wall thereof,
said projecting device including a pair of arcuate projections spaced apart from one another with a gap between adjacent ends thereof,
said hinge leaf having a shoulder spaced away from said counterbore and said cover including a plate carrying said arcuate projections and a hook portion engaging said shoulder. 35

4. A fastener-concealing hinge leaf construction comprising
a hinge leaf having a fastener hole therethrough and a counterbore connected to said fastener hole,
a fastener having a shank extending through said hole and an enlarged head seated in said counterbore,
a fastener cover engaging said hinge leaf and extending over said counterbore in concealing relationship therewith, 40

and means for securing said fastener cover to said hinge leaf,
said hinge leaf having a recess therein spaced apart from said fastener hole and said cover comprising a plate having a projecting device extending into said counterbore and a protrusion extending into said recess into gripping engagement with the side wall thereof.
5. A fastener-concealing hinge leaf construction comprising
a hinge leaf having a fastener hole therethrough and a counterbore connected to said fastener hole,
a fastener having a shank extending through said hole and an enlarged head seated in said counterbore,
a fastener cover engaging said hinge leaf and extending over said counterbore in concealing relationship therewith,
and means for securing said fastener cover to said hinge leaf,
said hinge leaf having an additional fastener hole and counterbore therein spaced apart from said first-mentioned hole and counterbore and also having a recess disposed in the space therebetween,
said securing means including a pair of projecting devices aligned with and extending into said counterbore,
and said cover comprising a plate carrying said projecting devices and a protrusion extending into said recess. 15
